SHEET TRANSFER GRIPPER MECHANISM

Arthur G. Jacobson, Chicago, Ill., assignor, by
mesne assignments, to The Miehle Printing
Press & Manufacturing Company, Chicago, Ill.,
a corporation of Delaware

Application March 29, 1946 Serial No. 658,077

6 Claims. (Cl. 271—53)

1

In its broader aspect my invention relates to means whereby registered sheets of material are conveyed in succession to a sheet carrying member of a printing press or other sheet handling machine.

More specifically, the invention pertains to an improvement in mechanism generally known in the art as oscillating stop gripper i. e. transfer gripper mechanism and of the class such as is described in the United States Letters Patent No. 1,790,457 issued to Joseph R. Blaine January 27, 1931.

The improvement primarily consists in the simplification of such mechanism as is illustrated in said patent and to render it more particularly adaptable for handling sheets fed in lapped sequence and at speed greatly in excess of heretofore customary feeding speeds.

In their joint application for United States Letters Patent Serial No. 741,118, filed April 12, 1947, now Patent No. 2,446,862 of April 12, 1949, Henri E. Peyrebrune and Bruno Pasquinelli have disclosed a novel step in the method of transferring to a printing press or the like mechanism sheets which are fed and registered in lapped relation and by which step it is possible to make available all of the time that can be gained during the sheet transferring period for the purpose of prolonging the time within which the sheets are to be registered.

In order to carry said improved method into effect, it is required to provide novel means applied to the gripper motion of the oscillating transfer grippers and therefore the primary object of my invention resides in the provision of simple and efficient mechanism whereby the fundamental principles of said improved method can be realized.

A further object of my invention is to provide an improved sheet transfer gripper mechanism wherein the gripper fingers and their associated gripper pads are mounted to rock about the same pivotal axis.

Another object of the invention consists in providing means whereby the sheet gripping elements after having engaged a registered sheet shall be positively locked against any unintended motion thereby assuring that accurate registering position of the sheet shall be maintained.

Still further objects and advantages gained by my invention will be made apparent to anyone skilled in the art from the following description and appended claims.

In order to exemplify the principle of my inven-

tion, I have illustrated one preferred form in the accompanying drawings, in which:

Figure 1 is a fragmentary sectional elevation of the improved gripper mechanism showing the sheet gripper fingers and associated pads closed on a registered sheet;

Figure 2 in a similar view depicts the gripper elements in their reeded position after a sheet has been transferred by them to grippers of an impression cylinder or the like sheet carrying member; and

Figure 3 illustrates the positions assumed by the grippers and associated pads as they return to grasp a succeeding sheet.

I have not illustrated any specific means whereby the stop gripper mechanism which embodies my invention may be actuated; however, it will be understood that any well-known type of such means can be utilized for that purpose. I make particular reference to the operating mechanism disclosed in my earlier United States Letters Patent No. 1,764,104 issued June 17, 1930.

Referring now to Figure 1 of the drawings, it will be seen that a sequence of lapped sheets A, B and C are supported on the registering table 10. The sheet A bears against the front guides 11 which are mounted on the rock shaft 12 to move into and out of their operative i. e. registering position in the direction indicated by the arrow N. The gripper fingers 14 and cooperating pads 15 have closed on the leading edge of the registered sheet A and are about to withdraw the sheet from the table 10 and transfer it to the impression cylinder or the like sheet carrying member 16 upon actuation of the transfer gripper operating mechanism, not shown, and whereby oscillatory motion is imparted to the shaft 17.

To this shaft is secured a bracket 20 preferably by means of a clamping device 18 and a Woodruff key 19 and the bracket carries the transfer grippers 14, pads 15 and their associated operating mechanism. The bracket 20 is also formed with an arm 22, the free end of which carries the gripper shaft 23 which extends across the entire width of the registering table 10 and to which are rigidly secured a series of gripper fingers 14 in a manner which is common practice in transfer gripper mechanism. Likewise secured to the shaft 23 is a link arm 24 to the free end of which is pivoted a spring actuated operating rod 25 by means of a pivot pin or stud 26 which also carries a cam roller 27. The arm 24, part of rod 25, stud 26 and roller 27 being located behind the bracket 20 as viewed in Figure 1, are shown in broken lines. The rod 25 extends through a lug 28 provided on

the bracket 20 and is urged upward by means of an expansion spring 29 which embraces the rod and which is placed between the lug 28, bearing against a washer 30 and a washer 31 adjustably positioned by means of a nut 32 threaded onto the free end of the rod 25.

Accordingly the action of the spring 29 will tend to move the gripper shaft 23 and therewith the fingers 14 in an anticlockwise direction as viewed in Figure 1 and also maintain the roller 21 in contact with the cam 33. This cam is mounted on the driving gear shaft, not shown, of the transfer gripper mechanism, rotates continuously in the direction indicated by the arrow and has such a contour that the operating and closing motion of the gripper fingers 14 is controlled thereby.

The gripper pads 15, corresponding in number with that of the series of fingers 14 carried by the shaft 23, are secured in any approved manner to a gripper pad bar 35 carried by an arm 36 and extending across the entire width of the registering table 10. Said gripper pad bar 35 having slots or notches, not shown, provided at appropriate locations to assume clearance for the arm 22 of bracket 20 when the arms 36 and thereby the pads 15 are withdrawn to the position shown in Figure 2. The arm 36 is mounted to pivot about the axis of the gripper shaft 23 and carries a cam roller 37 which is urged against a cam 38 by means of an expansion spring 39 through the intermediary of operating rod 40, pivoted to the free end of the arm 36. This rod extends through a lug 41 also provided in the bracket 20 and is urged upwards by the spring 39 which, similarly to the spring 29 of the rod 25, is held in position on the free end of the rod 40 by means of a washer 42 and nut 43 threaded onto the rod.

The novel arrangement of mounting the gripper fingers 14 and associated pads 15 so as to rock about the same pivotal axis provides the basis for a much simpler and more efficient operating stop gripper mechanism than any heretofore known, that is in which the fingers and pads are moved about separate pivotal axes.

In order to positively lock the gripper pads 15 and therewith the fingers 14 against any unintended motion and to take up any undesirable play between the cooperating elements, I propose to provide some means whereby the roller 37 shall be held in intimate contact with the cam 38. This cam, like the cam 33, rotates continuously in the direction indicated by the arrow and is mounted on the driving gear shaft of the transfer gripper mechanism and its contour is such as to control the movement of the gripper pads and the receding motion of the pads as well as of the gripper finger 14.

According to the preferred arrangement shown, I provide a locking bar 45 which is formed with a machined face 46 adapted to bear against a machined curved face 47 provided on the arm 36. This locking bar is attached to a suitable part of the press frame and is formed with elongated slots 48 to accommodate locking screws or the like 49 and 50. If any clearance develops between the machined faces 46 and 47, it can be readily taken up by loosening said set screws, readjusting the locking bar 45 so that its face 46 will again bear firmly against the cooperating curved face 47, and again tightening the set screws.

It will be understood that the locking bar 45 could be urged resiliently against the arm 36 in order to maintain intimate contact between the machined faces 46 and 47.

In order to simplify the showing of the gripper elements and associated operating mechanism in Figure 2 I have indicated the bracket 20 in broken lines.

5 The operation of the mechanism thus described is as follows:

Referring first to Figure 1, the sheet A is about to be withdrawn from the registering table 10 and the withdrawal commences at an accelerating speed as soon as the front guides 11 have moved down and away from the edge of the registered sheet A. By the time the transfer grippers have reached the position indicated by the broken lines in Figure 2, the front guides 11 have again moved up to register the next lapped sheet B. Upon transferring of the sheet A to the grippers 15 of the sheet carrying member 16, the roller 37 begins to ride over the low portion of the cam 38 and likewise the roller 21 commences to ride over the low portion of the cam 33, resulting in the receding of the fingers and pads from their plane of transfer operation which is indicated as D—D in Figure 1. Immediately thereafter the fingers and pads are returned to their sheet gripping position and by virtue of the contours of cams 33 and 38, these elements remain receded until the trailing edge of the sheet A has just passed over the front guides 11 and to a sufficient degree beyond them to permit the gripper fingers 14 to drop into the provided gap as shown in Figure 3, i. e. simultaneously with the passing of the trailing edge of the withdrawn sheet A over and beyond said guides, and then move up to close on the now registered sheet B the arm 36 remaining in its receded position until completion of the return stroke, whereupon the arm 36 is depressed until the pads 15 rest in position on sheet B, simultaneously locking the unit against the bar 45 to hold the gripper fingers 14 and pads 15 against any unintended motion. As the pads move down in position, the fingers 14 close on said pads, gripping the sheet therebetween. In the meantime the lapped sheet C will have advanced to the position assumed by the sheet B as shown in Figure 1.

While I have chosen to illustrate and describe a preferred form of my improved transfer mechanism and associated parts, it will be readily understood that the arrangement can be subject to constructional changes without departing from the principle of the invention and therefore I intend to cover any such mechanical modifications that will come within the terms of the appended claims.

55 I claim:

1. In sheet feeding mechanism of the class set forth, the combination comprising a support for sheets, sheet registering means, mechanism for transferring individual, registered sheets to a sheet carrying member, gripper fingers and cooperating pads carried by said mechanism, said fingers and pads being mounted for independent movement about a common axis, means for withdrawing said fingers and pads from their plane of transfer operation after a sheet to be transferred has been released by them, and means to return said fingers and pads to their sheet engaging position.

2. In sheet feeding mechanism of the class set forth, the combination comprising a support for sheets fed in lapped sequence, means for registering sheets while lapped, mechanism for transferring individual, registered sheets to a sheet carrying member, gripper fingers and cooperating pads carried by said mechanism, said fingers

and pads being mounted for independent movement about a common axis, means for withdrawing said fingers and pads from their plane of transfer operation after a sheet to be transferred has been released by them, and means to return said fingers and pads to their sheet engaging position while withdrawn.

3. In sheet feeding mechanism of the class comprising a support for sheets, sheet registering means, and mechanism for transferring individual, registered sheets to a sheet carrying member, the provision of sheet gripping elements carried by said mechanism and including gripper fingers and associated pads mounted for independent movement about a common axis, means for withdrawing said elements from their plane of transfer operation after a sheet to be transferred has been released by them, means to return said elements to their sheet engaging position, and means for positively locking said elements against any unintended circumferential movement while closing on a registered sheet.

4. In sheet feeding mechanism of the class comprising a support for sheets fed in lapped sequence, means for registering sheets while lapped, and mechanism for transferring individual, registered sheets to a sheet carrying member, the provision of sheet gripping elements carried by said mechanism and including gripper fingers and associated pads mounted for independent movement about a common axis, means for withdrawing said elements from their plane of transfer operation after a sheet to be transferred has been released by them, means to return said elements to their sheet engaging position while withdrawn, and means for rigidly locking said elements against any unintended circumferential movement while closing on a registered lapped sheet.

5. In sheet feeding mechanism of the class comprising a support for sheets, sheet registering means, and mechanism for transferring individual, registered sheets to a sheet carrying member, the provision of sheet gripping ele-

ments carried by said mechanism and including gripper fingers and associated pads mounted for independent movement about a common axis, means for withdrawing said elements from their plane of transfer operation after a sheet to be transferred has been released by them, means to return said elements to their sheet engaging position, and adjustable means for rigidly locking said elements against any unintended circumferential motion while closing on a registered sheet.

6. In a sheet transfer mechanism for conveying sheet material in lapped sequence from a support to a sheet carrying member, the combination of a drive shaft, brackets fixed on said shaft, a gripper shaft supported by said brackets, gripper fingers and gripper pads supporting means mounted coaxially on said gripper shaft, sheet registering guides, means for actuating said gripper fingers and pads for engaging the foremost one of a bank of lapped sheets in order to transfer it to the sheet carrying member, means for receding said fingers and pads from the path followed by the transferred sheet to clear it, and means operative during the return movement of the gripper fingers to project them into and beyond said path simultaneously with the passing of the trailing edge of the withdrawn sheet over and beyond said registering guides.

ARTHUR G. JACOBSON.
